(57) CLAIM

The ornamental design for a decorative accessory for boots and like footwear, as shown and described.

DESCRIPTION

FIG. 1 is a side elevational view of a decorative accessory for boots and like footwear showing my new design;

FIG. 2 is a top plan view thereof;

FIG. 3 is a rear elevational view thereof;

FIG. 4 is a front elevational thereof;

FIG. 5 is a bottom plan view thereof; and,

FIG. 6 is a perspective view thereof.

The broken line showing of footwear is included for the purpose of illustrating and forms no part of the claimed design.
